Patented May 20, 1969

214,154

LADY'S SHOE

Aiko Miyashita Hormann, 16550 Chattanooga Place,
Pacific Palisades, Calif. 90272

Filed June 13, 1968, Ser. No. 12,331

Term of patent 14 years

Int. Cl. D2—04

U.S. Cl. D2—302

FIG.1.

FIG.2.

FIG.3.

FIG.4.

FIG.5.

FIG.6.

I claim:

The ornamental design for a lady's shoe, substantially as shown.
